UNITED STATES PATENT OFFICE

2,235,632

METHOD OF FINGERPRINTING

William Heinecke, West Orange, N. J., assignor to
 Graphic Arts Research Corporation, Verona,
 N. J.

No Drawing. Application October 3, 1939,
 Serial No. 297,662

5 Claims. (Cl. 41—26)

This invention relates to new and improved methods of fingerprinting, designed to allow the rapid taking of fingerprint impressions from a person, upon plain untreated papers, without the usual objectionable usage of printer's ink, and 5 also designed to permit the employ, if desired, of non-toxic chemicals. The invention primarily involves the application of chemical principles to the present inconvenient method of making fingerprints, although my invention also includes 10 certain mechanical methods for the making of fingerprints which avoid the application of objectionable substances to the fingers of the person fingerprinted.

Heretofore, the most common method of making fingerprints was to apply printer's ink upon the fingers of the subject, and then directly impress the inked fingers upon paper. This method is objectionable, because the subject's fingers will 15 be badly stained, with the result that universal fingerprinting, for means of identification, has met with opposition. Also, under applicant's Patent No. 2,082,735, there has been in use, to a moderate degree, the method of impregnating 20 special papers with chemicals, which paper may have fingerprints developed thereon, by impressions made from the finger tips of the subject, by virtue of re-agent chemicals being applied from the fingerprints to the specially prepared paper 25 by impressional contact. However, the impregnated paper method has been found to be too expensive for wide use, although the same has been employed in certain banks and hospitals. Also, there is suggested in Patent No. 1,700,262, granted 30 to the present applicant, Dr. William Heinecke, the use of certain photographic methods for making fingerprints.

Therefore, it is an object of my invention to provide a simple economical method of taking 35 fingerprints, upon plain untreated papers, by the application of chemical principles without the necessity of using staining substances and preferably by the employ of non-toxic compositions.

It is a further object of my invention to provide 40 a simple chemical re-agent, which is stainless, which can be applied to the finger tips for impressional contact upon untreated papers, the impressions of which may be developed simply by the use of heat, or light, or heat and light in 45 conjunction, or in certain instances, merely by oxidation. This method will hereinafter be identified as the "single re-agent" method.

It is a further object of my invention to employ 50 a non-staining chemical re-agent for application 55 to the subject's finger tips, thus causing a finger-

print impression on plain paper by impressional contact, the impressions of which may be developed into clear fingerprints by the application of a second chemical composition: the application of the second chemical composition may be accomplished by the use of the same in a colorless spray form, or a colorless powder, or by wet pads or volatile vapors. This method will be referred to hereinafter as the "two re-agent" method. 5

It is a further object of my invention to provide 10 a simple mechanical method of making fingerprints which involves the application of a thermoplastic material to the finger tips of the subject to make an impression upon plain untreated paper, with subsequent dusting of the thermoplastic impression formed thereby with a colored 15 powdered material, such as powdered asphalt, by dusting, and then fixing the fingerprints formed thereby by heat.

It is also a further object of my invention to 20 provide in a suitable cake or paste, or ink pad, or liquid form, the above mentioned chemical reagents so that they may be conveniently utilized by the subjects to be fingerprinted, and it is further my intent, for purposes of economy to utilize 25 plain untreated paper.

It is a further object of my invention to produce 30 fingerprints by my method which are brownish or black (namely non-actinic colors) so that the same may be photographed.

Also, it is my purpose to permit the making of 35 fingerprint impressions particularly by the use of non-toxic, non-staining chemical substances, with the view that the economies and conveniences of such methods will eliminate the present prejudices to universal fingerprinting, with the attendant manifest advantages.

In my method, identified above as the "single 40 re-agent" method, I utilize plain untreated paper and develop after impressional contact, as indicated above, by heat or light, or heat and light together, or merely by oxidation.

For the purposes of illustration only, I will now 45 describe certain examples of the "single re-agent" method:

Example 1

By weight, one part of alloxanthine and 10 parts of oxalic acid, together with 50 parts of glycerin as a vehicle may be used as a colorless 50 non-toxic chemical "inking" substance for the giving of impressional contact finger prints upon plain untreated paper, and may be developed by the application of a moderate degree of heat alone, temperatures in the neighborhood of about 55

250 degrees F. being sufficient. If desired, a $\frac{1}{2}$ part of indoline may be substituted for the alloxanthine above.

Example 2

5 By weight, two parts of stannous chloride and one part of sodium thiosulphate, together with about 50 parts of glycerin and one part of water, as a binder, will serve to make impressional finger 10 prints upon plain untreated paper under conditions as indicated in Example 1.

Example 3

15 By weight, one part of resorcin and one part of sodium nitrate in about 30 parts of glycerin will develop by heat.

Example 4

20 One part of formaldehyde and one part of cinnamic acid and about 30 parts of glycerin will develop by heat.

Example 5

25 All soluble nitrates, for example, one part of bismuth nitrate in a colloidal vehicle comprising one part gum arabic, one part water and one part glycerin may be developed by heat.

Example 6

30 One part silver phosphate dissolved in a solution comprising one part citric acid, 10 parts glycerin, 2 parts oleic acid will make contact impressions which may be developed by light.

Example 7

35 One part silver stearate, 20 parts glycerin, 10 parts alcohol may be utilized to make impressional contacts developable by light, or heat, or both jointly.

Example 8

40 Two parts bismuth nitrate, two parts sodium thiosulfate, 40 parts glycerin and 10 parts water may be developed by heat.

Example 9

45 Five parts nickel nitrate, 50 parts glycerin and four parts of potassium sulfocarbonate may be developed by heat.

Example 10

50 One part of silver fluoride, together with a vehicle comprised of 75 parts castor oil and 75 parts of glycerin, will serve as a chemical "inking means" to give fingerprint impressions which may be developed by the use of light alone.

55 *Example 11*

Ten parts of silver chloride may be substituted for the silver fluoride in Example 10, if desired, with like results.

60 *Example 12*

The formula given in Example 10 may be developed by heat and light together.

Example 13

65 Although slightly toxic, one part of potassium silver cyanide ($KAgCn2$) in 50 parts of glycerin in another binder may be developed by heat and light jointly.

70 Examples of my so called "two re-agent" method for making fingerprints are as follows:

Example 14

75 Although toxic, any copper, bismuth or iron salt reacted with sodium diethyl-dithiocarbamate (the latter in a 5% water or alcohol solution may

be utilized: more specifically, one part of copper nitrate in 40 parts water or alcohol, plus a vehicle of about 40 parts of gum arabic, may be utilized in pad form, and developed by the application of the said sodium diethyl-dithiocarbamate 5 solution applied in spray form or by a pad, or in any convenient manner. Alternatively, the sodium diethyl-dithiocarbamate may be applied in powder form, while the copper nitrate impressions are moist, particularly conveniently after 10 sodium diethyl-dithiocarbamate is combined with starch powder.

Example 15

15 By weight, one part of para-amidophenetol in 10 parts of water, plus a vehicle of about 11 parts of gum arabic, may be utilized for making the impressional finger print impressions by contact upon plain untreated paper, and such impressions may be developed by utilizing a 10% chloryl hydrate solution in water or alcohol.

Example 16

20 By weight, 20 parts of furfural hydrochloride and 30 parts of glycerin solution may be used in Example 15 and the impressions developed by the use of a saturated solution of urea in a 10% alcohol and water solution. If desired, the urea could be used in powdered form to develop such impressions while the impressions are wet.

Example 17

25 A 5-10% solution of para nitrosodimethylaniline in glycerin may be utilized from a pad to make contact impressions and may be developed by means of a chemical reagent in powder form 35 such as beta naphthol or gallic acid.

Example 18

30 One part of furfural alcohol in a vehicle comprised of one part of di-ethyline glycol, or polymers thereof, may be developed by contact with any mineral acid.

Example 19

35 One part of cinchoine sulphate in five parts of glycerin may be developed by contact with a saturated alcoholic solution comprised of 100 parts potassium iodide and 1 part iodine.

Example 20

40 Five parts of citrophen in 50 parts of glycerin may be developed by a 10% sodium carbonate aqueous solution or sodium carbonate in powdered form.

45 A third manner of conveniently making fingerprints is my so called "mechanical" method. In this method, waxy heat thermoplastic material may be utilized in cake or paste form applied by the impressional contact method to plain untreated paper and then dusted with appropriate powders, as may be evident in the following examples:

Example 21

50 By weight, 85% paraffin or ceresin waxes are made slightly tacky by the addition of 10% of rosin and 5% castor oil. Such substances may be utilized to coat the ridges of the finger tips and contact impressions made upon plain untreated paper. Thereafter asphaltum nigrosine or other coloring agents in powder form will be dusted upon the impressions, and the same will be subjected to heat, causing the wax to dissipate in the paper substantially and leave the as- 75

phaltum or nigrosine powder adhering in definite fingerprint lines to the paper.

Example 22

5 One part of ethanolamine, one part rosin and one part shellac may be utilized to make impressional contacts upon plain untreated paper and then dusted with dihydroxyanthrachinone.

10 The methods explained above are new and unique and once understood, may be the subject of various variations, particularly by substitution of the various chemical compositions suggested. The chemicals involved may be utilized 15 in cake form, paste, pads, etc., and produce non-actinic colors. It will be observed that with the exception of the example involving copper salts, that the substances are all non-toxic and are stainless.

20 In the event that the chemical compositions used for making the impressional contact are colorless, a small amount of an appropriate non-staining substance, such as one of the alizarin dyes, may be added to the chemical compositions, in order that it may be observed as to whether 25 the contact impressions of such are perfect, prior to the development thereof. In this connection, it is obvious that the non-staining substance used must be compatible with the chemical composition used for making the impressions.

30 Accordingly, the examples given are not to be deemed as limiting the invention; for the scope thereof reference should be had to the appended claims.

35 Having described my invention, what is claimed now is:

1. The method of producing finger prints up-

on plain untreated papers which includes applying contact impressions of the fingers to the paper by means of substantially non-staining chemical compositions which are inert to the paper and to the epidermis of the human body and developing the chemical compositions of said impressions solely by heat. 5

2. The method of producing finger prints upon plain untreated papers which includes applying contact impressions of the fingers to the paper by means of substantially non-staining chemical compositions and developing the impressions solely by light. 10

3. The method of producing finger prints upon plain untreated papers which includes applying contact impressions of the fingers to the paper by means of substantially non-staining chemical compositions and developing the impressions by light and heat jointly. 15

4. The method of producing finger prints upon plain untreated papers which includes applying contact impressions of the fingers to the paper by means of substantially non-staining chemical compositions which are inert to the paper and to the epidermis of the human body and developing the chemical composition of said impressions solely by oxidation. 20

5. The method of producing finger prints upon plain untreated papers which includes making contact impressions of the fingers upon the paper by means of a slightly tacky non-staining thermoplastic substance, dusting the impressions with colored powder, and then applying heat to the impressions. 30

35 WILLIAM HEINECKE.
